HAT BASKET

Joseph Delgatto, Lake Geneva, Wis.

Application March 22, 1948, Serial No. 16,189

2 Claims. (Cl. 223—23)

1

This invention relates to certain new and useful improvements in hat baskets of a foraminated construction and especially adapted for use in the cleaning operation of a hat.

Prior to my concept it was the common practice in the cleaning of a hat to perform this cleaning operation by hand. This was accomplished by holding the hat in the hand and by applying by hand the cleaning compound thereto; or it was accomplished by placing the hat upon a block and then applying by hand the cleaning compound thereto. This operation involves considerable time and effort on the part of the operator.

My invention has for its principal object the provision of a hat basket within which a hat to be cleaned is loosely confined so that the hat and the basket may be placed in the revolving drum of a clothes cleaning apparatus and subjected in the revolving of the drum to the cleaning compound. After this operation, the basket with the hat confined therein may be removed from the cleaning apparatus and placed with other hats or other garments in a centrifugal drying apparatus. At the completion of this operation, the basket is removed from the drying apparatus and the hat is ready for the blocking process.

Another and equally important object of the invention is to provide a basket for the purposes herein stated, which can be manufactured at an economical cost.

Other objects will appear hereinafter.

The invention consists in the novel combination and arrangement of parts to be herein-after described and claimed.

The invention will be best understood by reference to the accompanying drawings showing the preferred form of construction, and in which:

Fig. 1 is a perspective view of my improved hat basket showing the top portion thereof in partial open position;

Fig. 2 is a top plan view of the basket embodying my invention;

Fig. 3 is a sectional detail view taken substantially on line 3—3 of Fig. 2.

The several objects of my invention are accomplished by the preferred form of construction shown in the accompanying drawings.

My improved hat basket includes two complementary structures 10 and 11, the structure 10 constituting a top hat covering lid and the structure 11 a hat supporting base. Each of these structures is of a foraminated construction.

They each comprise an outer ring 12 providing, together with an inner ring 13, a rim. The inner

2

and outer rings are spaced apart from each other by spacing bars 14. Connected to the inner rings 13 are crowns 15 and 16. The crown 15 is adapted to closely fit over the crown 16. Each of these 5 crowns comprises spaced bars 18 properly spaced from each other by spacing rings 19. The rings and the bars may be connected together in any suitable manner, such for example by means of sleeves 20 formed in the bars.

10 The lid and base are hingedly connected together as at 21. A suitable latch 22 is carried by the outer ring 12 of the base 11 and is adapted for latched engagement with the outer ring 12 of the lid 10 whereby to releasably latch the lid 15 to the base.

15 In use, the hat 23 to be cleaned is arranged in the basket with the crown 17 thereof disposed between the crowns 15 and 16 of the lid and base 10 and 11, and with the rim 24 of the hat positioned between the rims of the lid and base. 20 The size of the lid and base is such that when the hat 23 is confined in the basket with the lid latched to the base by the latch 22, there will be sufficient looseness between the hat and the 25 lid and the base so that during the cleaning operation, the cleaning compound may be unobstructed in its movement over and in contact with all surfaces of the hat. If it were otherwise, the 30 cleaning compound during the cleaning operation may not find its way beneath the bars.

As before stated, the basket with the hat contained therein is submerged in the cleaning compound with other wearing apparel or with other hats in a cleaning apparatus of the type usually 35 involving an agitator or a revolving drum. After the cleaning operation, the basket with the hat therein, together with other like baskets containing hats or with other wearing apparel, is placed in a drying apparatus usually of the centrifugal type. The basket maintains the shape 40 and stability of the hat during both of these operations. If desired, however, after the drying operation the hat may be subjected to a blocking process.

45 By the arrangement of a hat basket constructed in accordance with the foregoing description a number of hats may be cleaned in one operation. This is a great advantage over the single cleaning operation of hats as is performed by hand.

50 While I have illustrated and described the preferred form of construction for carrying my invention into effect, this is capable of variation and modification without departing from the 55 spirit of the invention. I, therefore, do not wish

to be limited to the precise details of construction set forth, but desire to avail myself of such variations and modifications as come within the scope of the appended claims.

Having thus described my invention, what I claim as new and desire to protect by Letters Patent is:

1. A basket in which a hat is adapted to be confined during a cleaning and drying process comprising two interfitting complementary structures, one providing a base upon which the hat is adapted to be mounted and the other a lid adapted to fit over the hat on the base, the said lid and said base being of a size such as to permit freedom of movement of the hat therebetween, and said base and lid each comprising concentrically arranged ring elements connected together by spaced bars to provide a relatively flat rim and other bars connected to the inner of said ring elements to provide a crown extending upwardly from the inner ring element.

2. A basket in which a hat is adapted to be confined during a cleaning and drying process comprising two foraminated interfitting complementary structures, one providing a base upon which the hat is adapted to be mounted and the other a lid adapted to fit over the hat on the base, the said lid and said base being of a size such as to permit freedom of movement of the hat therebetween, a hinge connection between said lid and said base, and latch means for latching said lid and said base in interfitting relation with respect to each other.

JOSEPH DELGATTO.
